US00D870690S

(12) **United States Design Patent** (10) **Patent No.:** **US D870,690 S**
(45) **Date of Patent:** **** Dec. 24, 2019**

(54) **MOBILE PHONE**

(71) Applicant: **Beijing Xiaomi Mobile Software Co., Ltd.**, Beijing (CN)

(72) Inventors: **Yanlin Xiao**, Beijing (CN); **De Liu**, Beijing (CN); **He Shan**, Beijing (CN)

(73) Assignee: **BELJING XIAOMI MOBILE SOFTWARE CO., LTD.**, Beijing (CN)

(**) Term: **15 Years**

(21) Appl. No.: **29/621,764**

(22) Filed: **Oct. 11, 2017**

(51) LOC (12) Cl. **14-03**

(52) U.S. Cl.

USPC ..... **D14/138 R**; D14/341
